Primary Examiner — T. Chase Nelson*Assistant Examiner* — Mark Cavana(74) Attorney, Agent, or Firm — Montgomery Patent & Design, LLC; Robert C. Montgomery; Joseph T. Yaksich(57) CLAIM

The ornamental design for a urine sample cup holder, as shown and described.

DESCRIPTION

FIG. 1 is a perspective view of a urine sample cup holder depicted in use with a urine sample cup, showing my new design;

FIG. 2 is a perspective view of the urine sample cup holder;

FIG. 3 is a front view thereof;

FIG. 4 is a rear view thereof;

FIG. 5 is a left side view thereof with a right side view being a mirror image;

FIG. 6 is a top view thereof; and,

FIG. 7 is a bottom view thereof.

The broken line showing of a urine sample cup in FIG. 1 is for the purpose of illustrating environmental structure and forms no part of the claimed design.
